(57) **CLAIM**

The ornamental design for a cap for an ultrasound probe, as shown and described.

DESCRIPTION

FIG. 1 is a front perspective view of a cap for an ultrasound probe shown attached to an ultrasound probe, showing our new design;

FIG. 2 is a rear perspective view of the cap for an ultrasound probe illustrated in FIG. 1, shown attached to an ultrasound probe;

FIG. 3 is a front elevation view of the cap for an ultrasound probe illustrated in FIG. 1, shown attached to an ultrasound probe;

FIG. 4 is a first side elevation view of the cap for an ultrasound probe illustrated in FIG. 1, shown attached to an ultrasound probe;

FIG. 5 is a top perspective view of the cap for an ultrasound probe illustrated in FIG. 1, shown in isolation;

FIG. 6 is a bottom perspective view of the cap for an ultrasound probe illustrated in FIG. 5;

FIG. 7 is a top view of the cap for an ultrasound probe illustrated in FIG. 5;

FIG. 8 is a front elevation view of the cap for an ultrasound probe illustrated in FIG. 5;

FIG. 9 is a first side elevation view of the cap for an ultrasound probe illustrated in FIG. 5;

FIG. 10 is a bottom view of the cap for an ultrasound probe illustrated in FIG. 5;

FIG. 11 is a rear elevation view of the cap for an ultrasound probe illustrated in FIG. 5, and;

FIG. 12 is a second side elevation view of the cap for an ultrasound probe illustrated in FIG. 5.

The broken lines are included for the purpose of illustrating portions of the cap for an ultrasound probe that form no part of the claimed design.

1 Claim, 5 Drawing Sheets
